WELL TOOL

Bob Young, Houston, Tex.

Application February 25, 1939, Serial No. 258,392

7 Claims. (Cl. 166—12)

The invention relates to a well tool and more particularly to a tool which is adapted to be lowered into a well bore upon a tubing string and to form a pack-off at a desired level.

In deep well operations such as the drilling and production of wells it is frequently desirable to provide a pack-off between a tubing string and the surrounding well bore or tubing. As examples of such operations reference is made to sample taking or formation testing, cementing, screen cleaning, etc. In such cases a period during which a device is stationary within a well may result in sticking of the device by sedimentation, caving, heaving or the setting of cement where cementing is being carried out.

It is an object of the invention to provide a tool which includes a packer and which is so constructed that the operating string and portions of the tool may be rotated after the packer is set.

It is also an object of the invention to provide a device of the class described in which a mandrel is rotatably connected to the remainder of the device.

Another object is to provide a device which includes an anchor and packer assembly in which the anchor and packer may be successfully set by the application of lifting force upon the lowering mechanism.

Still another object is to provide a device of the class described to be attached to a tubing string and in which slips may be initially set by pumping fluid downwardly thru the string and device.

The foregoing objects together with other objects will be apparent from the following description taken in connection with the accompanying drawings in which Figs. 1 and 2 are elevational views partly in section showing an embodiment of the invention.

Fig. 3 is a sectional view taken on the line 3—3 of Fig. 1.

Fig. 4 is a sectional view taken on line 4—4 in Fig. 1.

Fig. 5 is an assembly view partly in section showing the relative position of parts when the tool is set within the tubing string in a bore hole.

Fig. 6 illustrates a modification of the packer construction shown in Figs. 1 and 2 whereby it is possible to initially set the anchor mechanism by pumping fluid downwardly thru the device.

Fig. 7 is a fragmental view showing the construction of Fig. 6 with the parts in respective

positions when the anchoring mechanism is actuated.

Fig. 8 illustrates the relative position of parts in the modified construction when both the anchor and packer are set.

In Figs. 1 and 2 an embodiment of the invention is shown attached to a tubing string 1 and as comprising a cylindrical body member or mandrel 2 surrounded by a pack off assembly 10 generally designated as 3.

The reducer connection 4 interconnects the tubing 1 and the body 2 the latter of which terminates at its lower end in a collar 4' provided with threads 5 whereby a suitable tool 15 may be connected thereto and rotated by rotative effort imparted to the tubing string 1. The mechanism for lowering the device while in inoperative position to a desired level within a casing or tubing 6 and thereafter setting the 20 device at such desired level will now be described.

The assembly 3 includes an antifriction bearing 10 interposed between upwardly facing shoulder 11 on the collar 4' and a lower packer ring 12 mounted on mandrel 2. Surmounting 25 the ring 12 and surrounding the body 2 is an expandible packer ring 13 reduced peripherally at 14 to fit within a complementary recess in the ring 12.

In a similar manner the upper end of the 30 sleeve 13 is reduced peripherally at 15 to fit within a recess in expander member 16 which is slidably mounted on mandrel 2. This expander member is tapered at 17 to provide expanding movement to slips 18 surrounding the 35 expander member and provided with upwardly projecting teeth 20 for engagement with the casing 6 when the tool is in use.

Above the tapered portion 17 the expander member has a cylindrical portion 19 which extends upwardly to a point closely adjacent the shoulder 21 at the lower end of the connector 4.

Surrounding the cylindrical portion 19 of the expander member is a spring cage 22 provided with bowed springs 23 which are secured within 45 slots 24 in the surface of member 22, and adapted to engage the casing 6 to provide sufficient frictional contact that there is a tendency for the anchor packer assembly 3 to remain at any desired position within the casing. An internal groove 25 in the lower end of the spring cage 22 receives flanges 26 at the upper ends of the slips 18 whereby these slips are freely carried at the lower end of the spring cage and may be moved radially of the device in a manner 50 that will be more fully apparent.

The connector 4 is provided with projections or trunnions 30 which are adapted to move into the open ended slots 31 of cage 22 and to engage within the undercut portion 32 of the slots. It is believed apparent that as the device is being lowered into or withdrawn from the casing 6, the anchor packer assembly 3 is caused to move together with the remainder of the device thru the driving force exerted between the projections 30 and the undercut portion 32 of the slips 31.

The operation of the construction as above described is believed apparent. Attention is directed to the fact that when the device has reached a desired level within the well the tubing string 1 may be rotated left handedly sufficiently to disengage the projections 30 from within their respective slots in the cage 22. A lifting effort is then applied to the tubing string 1 whereupon initial movement of the body 2 relative to the remainder of the device will cause the slips 18 to ride upon tapered surface 17 and thus be brought into engagement with the inner surface of the casing 6. This action is instrumental in fixedly anchoring the anchor and packer assembly within the casing.

Further lifting of the tubing string 1 will cause the pins 30 to move from within the open ended slots 31 and will at the same time exert sufficient force upon the lower packer ring 12 that the packer sleeve 13 will be brought into sealing engagement with the casing 6 so that the parts of the device will assume the relative positions illustrated in Fig. 5. In this manner an effective seal will be made between the body 2 and the casing 6. The provision of antifriction bearing 10 will, however, permit the tubing string 1 together with the body 2 to be rotated so that the tendency of the device to become stuck from sedimentation or other sources will be minimized.

The modification illustrated in Figs. 6, 7 and 8 is designed to enable the initial setting of the slips 18 by merely pumping fluid downwardly thru the bore within the body 2. This action is brought about by providing a chamfer in the recess in the expander member and the upper end of the packer sleeve 13' to form a small chamber 33. An opening 31' leads from the interior of the body 2 to the chamber 33.

It is to be noted that the channel in the expander member 16' in this construction is deeper than that shown in the embodiment of Figs. 1 and 2 and that the upper end of the packer member 13' is elongated to fit within this channel. Hence when fluid is pumped downwardly thru the tubing string 1 and the body 2, pressure is exerted within the chamber 33 and the expander 16' is moved upwardly to the position illustrated in Fig. 7. This provides an initial setting of the slips 18. Subsequent release of the body 2 from the spring cage 22 permits the tubing string 1 to be moved so that the packer sleeve 13' will move upwardly within the channel in the member 16'. At the same time the passage 31' will move upwardly to the position shown in Fig. 8.

The foregoing describes a construction embodying the invention which broadly comprehends a tool in which there is provided an anchor and packer assembly and which is so constructed that the tubing string to which the device is attached may be rotated after the packer has been set, whereby the numerous advantages of the invention are realized.

What is claimed is:

1. An oil well tool of the class described comprising a tubular body having a passage therethrough, an expander surrounding the body, a spring cage surrounding the body and releasably connected thereto, said cage including members adapted to engage cylindrical walls surrounding the tool and to resist movement of the cage relative to said walls, slips attached to the cage and movable radially outwardly upon relative longitudinal movement of the expander and cage, a packer surrounding the body below said expander and a thrust bearing between the lower end of the body and the packer whereby the tubular body may be rotated when the spring cage is released therefrom.
2. In a well tool of the class described, the combination of a cylindrical member, an anchor and packer assembly surrounding said member, said assembly including means for frictionally engaging cylindrical walls surrounding the tool, slips attached to said means, a packer below said slips, means for expanding said slips when said member is moved upwardly to expand the packer, and thrust bearing means between the member and the lower end of said packer.
3. In a well tool of the class described a cylindrical body, an expander member surrounding the body and movable relative thereto, a plurality of slips engageable by said expander member and movable outwardly to engagement with surrounding cylindrical walls, said expander member having a concavity at one end thereof, and a packer sleeve of expandible material having an end adapted to fit within said concavity, there being an opening in the body adjacent said concavity whereby fluid pressure within the body will move the expander member and effect initial setting of the slips.
4. In a well tool of the class described a cylindrical body, an expander member movably surrounding the body, said member having a cylindrical concavity in one end thereof, slips adapted to move outwardly upon the surface of the expander, a packer surrounding said cylindrical body and including a cylindrical surface fitting within said concavity, and a passage in said body for admitting fluid pressure from within the body to the interior of the concavity to move the expander.
5. In a well tool, the combination of a cylindrical member, an expander slidably surrounding said member and having an inwardly tapering peripheral surface thereon, a slip assembly including a plurality of slips adapted to ride upon the tapering surface and engage a cylindrical surrounding surface whereby the assembly is anchored to the surrounding surface, a packer ring rotatably mounted upon the member in opposed relation with the expander, an expandible packer surrounding the member between the expander and the ring, and a thrust bearing between the said cylindrical member and said packer ring whereby said member may be rotated relative to the packer.
6. In a well tool the combination of a cylindrical member, an expander slidably thereon, a slip assembly including a plurality of slips adapted to ride upon the expander and engage an adjacent coaxial surface when the member is moved axially thereof, an annular collar attached to said member, a packer ring surrounding the member adjacent said collar, a thrust bearing between the ring and collar, and an expandible packer surrounding the member be-

tween the expander and said ring, whereby the slips are set and the packer expanded to engage the member and the adjacent coaxial surface as the member is moved axially and simultaneously rotated.

7. In a well tool of the class described, the combination of a drill string, a tubular mandrel attached thereto and forming with the drill string a continuous bore, an expander member slidably surrounding the mandrel, and having an inwardly tapering surface on its periphery, a slip assembly including slips adapted to ride upon said tapering surface and engage a pipe surface sur-

rounding the tool when the string and mandrel are moved axially of a well bore, a releasable connection between the assembly and mandrel, a packer ring rotatably mounted upon the mandrel in opposed relation with the expander, and a packer surrounding the mandrel between said member and ring to be expanded by relative movement therebetween, whereby the string and mandrel may be rotated after the packer is set 10 to seal between the mandrel and the surrounding pipe.

BOB YOUNG.
